(57) CLAIM

The ornamental design for a pair of insoles, as shown.

DESCRIPTION

FIG. 1 is a top plan view of a right-hand insole of a pair of insoles, showing my new design;

FIG. 2 is a top inner side perspective view thereof;

FIG. 3 is a top outer side perspective view thereof;

FIG. 4 is a bottom outer side perspective view thereof;

FIG. 5 is a bottom inner side perspective view thereof;

FIG. 6 is a top plan view of a left-hand insole thereof;

FIG. 7 is a top inner side perspective view thereof;

FIG. 8 is a top outer side perspective view thereof;

FIG. 9 is a bottom outer side perspective view thereof; and,

FIG. 10 is a bottom inner side perspective view thereof.

The broken line portions of FIGS. 1-3 and 6-8 are included to show unclaimed subject matter only and form no part of the claimed design.
